UNITED STATES PATENT OFFICE.

EUGENE DIDION, OF BAGNOLET, FRANCE.

WASHING MACHINE.

Application filed April 7, 1925, Serial No. 21,405, and in France April 10, 1924.

This invention relates to a washing machine comprising a boiling tub in which is journaled horizontally a cylindrical basket provided with blades and pierced with holes and intended to hold washing.

The object of the invention is to obtain the automatic rotation of the basket by means of the motive force produced by the water boiling in the tub and which creates in it an upward current through the differences in density and the rising of the steam as it forms.

The invention consists essentially, for this purpose, in creating upon the half of the base of the tub which is faced by the idle surfaces of the blades, between this base and the basket, two chambers, one of which is formed on the base itself of the tub, in the entire length of the tub, by a plate incurved 20 coaxially to the basket, the said chamber being partly open at its lower end (towards the vertical axial plane) and connected at its upper end (towards the horizontal axial plane) to a second chamber of smaller capacity formed upon it by a plate incurved like the first one co-axially to the basket, and having an aperture at its lower part and a connecting passage at its upper part, each greater than the lower opening of the 25 first chamber.

The invention is illustrated by way of example in the accompanying drawing in which:—

Figure 1 is a section across the axis of rotation of the basket taken along the line I—I in Figure 2.

Figure 2 is a longitudinal section taken along the line II—II in Figure 1.

Figure 3 is a perspective view of the tub the front wall of which has been removed.

In Figures 1, 2 and 3, the channel 17 is fully open at its upper part to a channel 19 with a lower opening 20, while the lower part of the said channel 17 is partly closed by a plate 21 which only leaves two orifices 22 the cross section of which is less than that of the channel 19 and of its opening 20 which is itself less than the cross section of the channel 17. The tub being filled with

water up to a certain level, and also a part 50 of the channels 17 and 19, this water is made to boil by the application of external heat, and as the volume of the space or channel 17 is greater than that of the space or channel 19, and the latter has an orifice 55 20 the cross section of which is greater than the sum of the cross sections 22 of the former, it follows that the pressure generated in the channel 17 will escape, at least in part, through the channel 19 and its orifice 20 at an increased pressure or velocity, giving rise to a current which is added to the ascending current already produced in the interior of the tub by the differences of density and the rising of the steam as it is 60 formed, this current exerting a pressure on the blades which helps to rotate the basket.

What I claim is:—

A washing machine comprising in combination a tub for containing boiling water, 70 said tub having a hemispherical bottom, a cylindrical basket, said basket having holes pierced in it and being rotatively suspended in said tub, turbine blades carried on said basket, a main chamber formed on one half 75 of the bottom inner surface of said tub, curving coaxially with the basket and the lower end of such chamber being in open communication with the tub interior, a second chamber of smaller capacity curving 80 coaxially with the basket, being disposed centrally in relation to the main chamber and having a communication at its upper part with the said main chamber and an outlet aperture at its lower part, said passage and aperture being each greater than the lower openings of the main chamber, 85 said connecting passage forming a steam bell from which steam, issuing in the direction of least resistance through the smaller chamber having the largest orifice impresses upon the mass of water in the tub movements of flux acting upon the working surfaces of the blades in order to rotate the basket.

In testimony whereof I have signed my 90 name to this specification.

EUGENE DIDION.
